UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-RIGGING FOR RAILWAY-CARS.

1,140,162.

Specification of Letters Patent.

Patented May 18, 1915.

Application filed March 10, 1913. Serial No. 753,246.

To all whom it may concern:

Be it known that I, GEORGE A. JOHNSON, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying 10 drawings, forming a part of this specification.

My invention relates to improvements in draft rigging for railway cars.

The object of my invention is to provide 15 a draft rigging of high compression resisting capacity, and one of efficient operation.

In the drawings forming a part of this specification Figure 1 is a side elevation in vertical longitudinal section on line 1—1 of 20 Fig. 2 of a draft rigging embodying my invention. Fig. 2 is a plan view partly in horizontal section. Fig. 3 is a cross-sectional view on line 3—3 of Fig. 1. Fig. 4 is a cross-sectional view on line 4—4 of Fig. 25 5. Fig. 5 is a detail showing in perspective a friction shell. Fig. 6 is a further perspective view of the friction shell.

In the drawings 7, 7 represent draft sills or parts of the car frame to which the draft 30 rigging is attached, 8 the end sill, 9 the buffer block, 10 the draw bar carry iron, 11 the draw bar, having a transverse slot 12 to receive the coupler key 13, 14, 14 cheek plates suitably secured to the draft sills, 35 each being provided with the front stop shoulders 15, 15 and the rear stop shoulders 16, 16, and each being provided with a longitudinal groove 17 adapted to receive a limb 18 of the horizontal yoke 19.

40 The yoke 19 is forwardly provided with the transverse slots 20, 20 through which the coupler key 13 passes, and thus connects the draw bar with the draft yoke. Within the draft yoke is disposed the front fol- 45 lower 21 and the draft gear 22, the draft gear being supported against downward dis- placement by the tie plate 23.

The draft sills 7 preferably comprise a 50 pair of channel beams spaced apart with upper and lower outwardly turned flanges 24, 24 and 25, 25 respectively, and an angle iron 26 secured to the lower edge of each of said channel beams, the lower flange 25 of each channel beam being secured, pref- 55 erably by rivets, to the outwardly turned

adjacent flange 27 of the angle iron, and the said flanges 25 of each channel beam and the flange 27 of each angle iron being perforated to receive the bolts 28 which pass through the same and through the ends 60 of the tie plate 23. The said bolts also bear a clip 29, which is preferably extended along the length of the tie plate 23. Each clip 65 incloses the lower flange 25 of one of the channel beams, the adjacent flange 26 of the angle iron, and one end of the tie plate.

The draft gear 22 comprises a friction shell 30, preferably cylindrical in shape or circular in cross section, having an internal friction face 31, and being provided with a 70 preferably integral rearwardly extended loop 32. The friction shell 30 has at its rear end a preferably rectangular plate 33, the same being preferably integral with the said shell and integral with the loop 32, 75 the said plate serving as a rear follower, and adapted to engage the rear stop shoulders 16, 16 of the cheek plates.

The spring loop has a transverse opening 80 34, which is preferably rectangular in shape, and is provided at each side in preferable construction with outwardly turned strengthening flanges 35, 35. The said flanges are connected at their rear end in preferable construction by a plurality of 85 transverse plates 36, 36, which are preferably integral with the said flanges and with the said loop, the said flanges at their forward ends being preferably integral with the transverse plate 33.

At its rearward end the friction shell 30 is provided with a shoulder 37 formed within the transverse plate 33. Within the loop 32 are disposed a plurality of springs 38, 38, preferably two in number, the said 90 springs being arranged one above the other, as illustrated in Fig. 1 of the drawings, the said springs being seated at their rear end against the rear member 39 of the loop and at their forward ends against the rear face 40 of a movable spring seat 41. The said 95 movable spring seat is provided with an outwardly extended flange 42 adapted to engage the shoulder 37 at the rear end of the friction shell, the said spring seat being 100 in engagement at its forward end 43 with the friction mechanism 44 within the shell 32.

The friction mechanism 44 comprises a 105 plurality of friction shoes 45, preferably 110

three in number, in annular arrangement within the shell, each of said shoes having an outward friction face 46 adapted to engage the friction face 31 of the shell, and 5 each of said shoes being provided on its inner face with an anti-friction roller seat 47, within each of which is seated an anti-friction roller 48, each of said rollers engaging with the adjacent wedging face 49 10 of the wedge or spreader member 50. The wedge 50 at its forward end is in engagement with the front follower 21, and is provided with a recess 52 to receive the nut 53 of the connecting rod 54, which passes 15 through the said wedge and through a perforation 55 in the movable spring seat 41, which spring seat is rearwardly provided with a recess 56 to receive the head 57 of the said connecting rod.

20 The limbs 18, 18 of the horizontal yoke 19 are preferably turned toward each other at the rearward portions thereof, as indicated at the numerals 58, 58 in Fig. 2. The connecting member 59 between the said 25 limbs 18, 18 engages the rear end 60 of the spring loop 32.

On forward movement of the draw bar the draft gear is drawn forwardly by means 30 of the draft yoke against the front follower 21, thus bringing into compression resisting action the friction members within the shell 22, and the spring 38, 38 within the loop 32. On rearward movement of the draw bar the transverse plate 33 serves as a rear follower, 35 and engages the rear stop shoulder 16, the friction members within the friction shell, and the springs within the loop being rearwardly compressed thereby.

It will be observed that my invention permits 40 the use of standard stop members provided with the usual front and rear stop shoulders, and a draft gear in connection therewith having a shell longitudinally operating between the said stop shoulders, the 45 compression resisting power of the same being enhanced through the use of the rearwardly extended loop, which extends to a point between the draft members back of

the rear stop members, and thus enables the employment of compression resisting means 50 within the loop in addition to the usual compression resisting means which may be mounted in the longitudinal dimensions between the front and rear stop shoulders of the cheek plates.

55

I claim:—

1. In a draft gear, in combination, a friction shell, a spring loop connected to said shell, friction mechanism within the friction shell and springs within the loop, a 60 movable spring seat between the friction mechanism and the springs, the friction shell being rearwardly provided with a shoulder, and the spring seat being provided with a shoulder adapted to engage therewith in 65 normal position of the parts of the draft gear.

2. In a draft rigging, the combination with stop members, of a friction shell mounted between said stop members, the 70 shell being provided with a loop extending to the rear of the rear stop members, friction mechanism within the shell, twin arranged springs within the loop, and a yoke encircling said shell and loop and arranged 75 in a plane perpendicular to the plane of the loop, said yoke having the rear portions of the arms thereof inclined toward each other at the rear of the friction shell whereby the rear connecting member for the arms is 80 shorter than the distance between the arms where the arms pass by the friction shell.

3. In a railway draft rigging, the combination with stop members, of a friction shell having a vertically arranged loop extending 85 from the rear thereof and to the rear of the stops, said loop being open on the sides thereof, friction mechanism within the friction shell, springs within the loop, and a horizontally arranged yoke extending around 90 the friction shell and the loop.

GEORGE A. JOHNSON.
